PIANO CASE

Winsor D. White, Jr., Blowing Rock, N.C., assignor to D. H. Baldwin Company, Cincinnati, Ohio, a corporation of Ohio

Filed Nov. 20, 1964, Ser. No. 82,732

Term of patent 14 years

(Cl. D56—9)

The conventional keyboard is fragmentarily shown by means of broken lines and is continuous across the piano as indicated by the long dash dot lines.

I claim:

The ornamental design for a piano case, substantially as shown and described.
